Patented Nov. 4, 1924.

UNITED STATES PATENT OFFICE.

ROBERT C. EDWARDS, OF ELIZABETH, NEW JERSEY, ASSIGNOR TO RADIO CORPORATION OF AMERICA, A CORPORATION OF DELAWARE.

DESIGN FOR A CABINET FOR RADIORECEIVERS.

Application filed February 23, 1923. Serial No. 5,239. Term of patent 14 years.

To all whom it may concern:

Be it known that I, ROBERT C. EDWARDS, a citizen of the United States, and a resident of 6 Hillside Road, in the county of Union, city of Elizabeth, and State of New Jersey, have invented a new, original, and ornamental Design for Cabinet for Radioreceivers, of which the following is a specification, reference being had to the accompanying drawing, forming part thereof.

The single figure of the drawing is a perspective view of a cabinet showing my new design.

I claim:

The ornamental design for a cabinet for radioreceivers as shown.

ROBT. C. EDWARDS.
